TRAIN DISPATCHING SYSTEM FOR RAILROADS

Filed June 15, 1929

UNITED STATES PATENT OFFICE

WALTER W. WENHOLZ, OF ROCHESTER, NEW YORK, ASSIGNOR TO GENERAL RAILWAY SIGNAL COMPANY, OF ROCHESTER, NEW YORK

TRAIN-DISPATCHING SYSTEM FOR RAILROADS

Application filed June 15, 1929. Serial No. 371,091.

This invention relates to train dispatching systems of the synchronous selector type, and more particularly to the provision of means for increasing the number of distinctive control and indication messages which may be transmitted over a single message channel.

A synchronous selector system is intended to mean a system in which a plurality of message channels, each including the same 10 message wire, are completed sequentially in rapid sequence by two or more circuit closing means located at a local point and one or more distant points, which circuit closing means operate synchronously. As example of 15 such synchronous selector systems reference may be had to the prior application of N. D. Preston, Ser. No. 199,325, filed June 16, 1927, illustrating a system in which the selector includes synchronously operated rotatable 20 arms and in which the selectors are normally at rest, and the application of Hitchcock and Dicke, Ser. No. 345,667 filed March 9, 1929, illustrating a synchronous selector system, of the stepping relay type in which the stepping relays are normally at rest.

In accordance with the present invention it is proposed to control a distant polar-neutral relay to either of its three indicating 30 positions over a single message channel in a manner so that this relay may be placed in either of its energized positions in accordance with the polarity momentarily applied thereto, and may be placed in its de-energized condition by the momentary opening of the 35 message circuit, so that three distinctive conditions of this relay may be obtained. Further, it is proposed to distinctively indicate in the dispatcher's office whether or not a particular message channel is completed during 40 the particular instant during which it should be completed, and by the provision of such means it is indicated in the tower whether or not a distant track circuit, including a track relay having its front contact in the message 45 circuit is occupied or unoccupied.

Other objects, purposes and characteristic features of the invention will in part be obvious from the accompanying drawings and in part be described as the description thereof 50 progresses.

In describing the invention in detail reference will be made to the accompanying single drawing, in which the apparatus located in the dotted rectangle illustrates the apparatus in the dispatcher's office, the remaining apparatus being located at a distant 55 way station.

Referring to the drawings the rails 10 designate the main track rails of a single track railway system, having a passing siding PS 60 including track rails 11, the east end of this passing siding including a track switch S, having associated therewith the usual detector track circuit including a track relay T and a track battery 12.

This track switch S also has associated therewith switch box contacts 13, which are closed when this switch S assumes either of its extreme positions and which contacts are open if the track switch assumes an intermediate position. This, the east end of the passing siding PS is provided with a main east bound starting signal EM, a dwarf signal ED, a west bound entering signal WM and a take-siding signal WD. These signals 70 are controlled in accordance with the position of the track switch S, conditions of traffic ahead, and the position of the control relay Z, all in a manner conventionally shown and as described in the application of S. N. 75 Wight, Ser. No. 120,423 filed April 3, 1926.

The passing siding PS is merely representative of the entire railway system, which in practice includes many passing sidings, railway crossings and interlocking plants.

In the dispatcher's office D0 the entire railway system is reconstructed in miniature, as illustrated by the miniature passing siding ps. The east end of this miniature passing siding ps has associated with it the lever L and indicating lamp IL, which lamp is illuminated when the distant track relay T is de-energized, and is likewise illuminated when the switch S assumes an intermediate position. The dispatcher's office equipment also includes polar relays AR and BR, an indicating relay IR and an audible signal such as a bell BL. The relays AR and BR may be said to be snap action, in that momentary energization of the same by a potential of the proper 90 95 100

polarity will operate them quickly to the opposite position where they will be held by means associated with the relay.

The synchronous selector portion of the system, whether of the rotating arm or the stepping relay type, has been represented conventionally by the synchronously rotated arms A and A¹ and the message wire 15. This synchronous selector system may be one of the continuously operated type, or may be one where the synchronous selectors are normally at rest and are operated only for a few revolutions in response to each lever movement and each change in track circuit occupancy. The batteries 16 and 17 have been illustrated for conventional purposes, and instead of connecting the wires of the system to the plus terminal (B+) and the minus terminal (B-) of these batteries, the reference characters B+ and B- have been applied to those parts of the wiring system which are connected to these battery terminals, this in order to simplify the wiring arrangement and facilitating comprehension of the circuit arrangement. It is believed that the nature of the system illustrated embodying the present invention, as well as its operating characteristics, are best understood by considering the operation thereof, and for this reason the operation of the system will now be taken up.

Operation.—Let us first assume that the lever assumes its normal neutral position in which position only the contact L engages a stationary contact. Let us also assume that the arms A and A¹ are rotated in synchronism. Under the condition assumed the relays AR and BR in the dispatcher's office have their lower windings energized repeatedly once for each cycle of operation of the arm A. These circuits may be traced as follows:—beginning at the terminal B+ of the battery 16, the lower winding of the relays AR and BR in multiple, from whence these circuits are the same and constitute, wire 20, back contact 21 of the indicating relay IR, wire 22, contact segment 23 of the arm A, wire 24 to common return wire C connected to the midpoint of battery 16. Since the relays AR and BR are direct current polar relays of the permanent magnet stick type, the armatures thereof will not be physically moved, but they will merely remain in their left-hand position, as shown. Nothing will transpire at the way station at the east end of the passing siding PS, with the arms A and A¹ in position two, because the contact 58 of relay Z is open, so that we may proceed to assume other conditions of traffic and positions of the lever L.

Let us assume that the lever L is moved to its right-hand position, signifying east bound traffic. Under the condition assumed the circuits for the bottom windings of relays AR and BR are again momentarily com-

pleted at the second step in the operation of the synchronous selectors, and a local circuit is completed at the dispatcher's office when the rotating arm A assumes a position to contact with the stationary contact 3. This circuit may be traced as follows:—beginning at the terminal B+, contact 25 of the lever L, wire 26, upper winding of the relay AR, wire 27, contact 28 of the lever L, wires 29 and 30, contact segment 23 of the arm A, wire 31, to common return wire C. The circuit just traced when completed operates the relay AR to the right-hand position and simultaneously with the completion of this circuit the relay BR is operated to its right-hand position through the following circuit, including the message channel completed in the third position of the rotating arms A and A¹:—beginning at the terminal B+ of the battery 16, wire 35, upper winding of the relay BR, wire 36, contact 37 of the lever L, wire 38, contact 3 and arm A of the synchronous selector in the dispatcher's office, message wire 15, arm A¹ and contact 3 of the synchronous selector at the way station, wire 39, front contact 40 of the track relay T, wires 41 and 42, back contact 43 of the control relay Z, wires 44 and 45, the winding of the relay Y and the upper winding of the relay X in multiple, wire 46, to common return wire C connected to the midpoint of battery 16. It should be noted that there is a multiple branch in the circuit just traced, including the switchbox contact 13 in multiple with the back contact 13 of the relay Z, both contacts of which are now closed.

The completion of this circuit supplies current to operate the relay BR and the relays X and Y to their right-hand position. Since the relays AR and BR in the dispatcher's office now both assume the right-hand position the indicating relay IR will remain de-energized and since these relays AR and BR operate simultaneously the audible signal BL is not sounded. Also, with the relays X and Y operated to their right-hand position simultaneously the control relay Z is energized to its right-hand position through the following circuit:—beginning at the terminal B+, contact 48 of the relay Y, wires 49 and 50, winding of the control relay Z, wire 51, contact 52 of the relay X, to the terminal B- of the battery 17. The control relay Z is thus operated to its right-hand position in response to operation of the lever L to its right-hand position. With the polar contact 55 in the right-hand position and the neutral contact 56 in its raised position, the east bound signal EM or ED may be cleared, providing traffic conditions in advance are favorable, and depending upon the position of the track switch S.

Let us now observe the operation of the system as the synchronous selector arms A and A¹ continue to operate without any

change in the position of the lever L, the track switch S or the track relay T, bearing in mind that the contact arms A and A¹ are rotating in a clockwise direction as indicated by the arrows, it is noted that these arms just before completing an entire revolution engage the stationary contacts 2. At this point in the rotation of the contact arm A, the relays AR and BR are both operated to the left, but they only remain there momentarily because they are returned to the right-hand position, for reasons heretofore explained, when the contact arm A assumes the third position and engages the contact 3. At the distant way station, however, one of the relays X and Y, namely the relay X, is returned to its left-hand position when the arm A¹ assumes its second position in engagement with the stationary contact 2. The circuit for operating the relay X to the left-hand position is completed when the arm A¹ assumes a position to engage the contact 2, and may be traced as follows:—beginning at the terminal B+ contact 48 of the relays Y assuming its right-hand position, wires 49 and 57, front contact 58 of the relay Z assuming its attracted position, wire 59, bottom winding of the relay X, wire 60, contact segment 61 of the arm A¹, wire 62, to common return wire C connected to the midpoint of battery 17. The completion of this circuit will return the relay X to a position opposite to that which it previously occupied, this because the contact 48 of the relay Y still assumes the position to which it was previously operated. With the relays X and Y out of correspondence, namely, the relay Y assuming the right-hand position and the relay X assuming the left-hand position, the terminal B+ is connected to both terminals of the control relay Z, so that the control relay Z is de-energized, but by reason of its slow-acting characteristics remains in its energized position a moment longer, and if the relays X and Y are again operated to corresponding positions when the arm A¹ reaches the third position, in engagement with the contact 3, the relay Z will not actually assume its de-energized position. When the rotating arm A¹ reaches the third position, in engagement with the stationary contact 3, the circuits for the relays X and Y, heretofore traced, are again completed, with the exception that the current passes only through the switchbox contact 13 instead of passing through the contacts 13 and 43 in multiple, as was heretofore the case, thereby operating the relays X and Y to their right-hand position. Since the relay Y still assumes its right-hand position, its armature is not actually moved, but the relay X, which has been operated to its left-hand position in the meantime, is again returned to its right-hand position, thereby reapplying energy to the control relay Z of the same po-

larity heretofore applied thus maintaining the control relay Z energized. It should be noted that the conventional showing of the relay Z signifies slow action, this relay Z being sufficiently slow dropping to avoid actual dropping of its contacts while the relay X is out of correspondence with relay Y during movement of the arm A¹ from the second to the third position. 70

Thus far we have considered the operation of the system with the lever L in the neutral position and with the lever L in its right-hand position. Let us now assume that the dispatcher wishes to place all of the signals EM, ED, WM and WD at the east end 75 of passing siding PS at stop, and in order to do so moves his lever L to the middle neutral position. With the lever L moved to the neutral position the relays AR and BR in the dispatcher's office will be returned to 80 their left-hand position the next time the arm A engages the stationary contact 2, and remain there for reasons heretofore explained, namely because no energy can be applied to their upper windings. 85

Let us now, however, observe what takes place at the way station, in that the circuit heretofore traced over the third channel, including the contacts 3 and the message wire 15, is now open at the contact 37 of the lever 90 L. When the rotating contact A¹ reaches the second position, in engagement with the contact 2, the relay X is returned to the left-hand position through the medium of the closure of a circuit through its bottom winding of relay X and heretofore traced, and as the contact arm A¹ reaches the third position in engagement with the contact 3 nothing transpires at this way station, so that the relays X and Y thereafter remain in the position shown in the drawings, causing the relay Z to assume its de-energized position and opening the signal circuit at the neutral contact 56 of the control relay Z. It is thus apparent that the single message circuit mentioned is capable of energizing the relay Z to either of its polar positions and is also capable of de-energizing the polar-neutral control relay Z. 100

Let us now observe the functioning of the system when the control lever L is moved to its left-hand position, presumably because the dispatcher wishes west bound traffic to move over the switch S at the east end of the passing siding PS. With the lever L in its left-hand position, the engagement of the contact segment 23 with stationary contacts in the second position of the cycle of operation, causes the relays AR and BR to be energized to their left-hand positions for reasons heretofore given, but since these relays AR and BR already assume the left-hand position their armatures are not moved. Upon engagement of the arm A with the stationary contact 3, the following circuit for the upper 110 115 120 125 130

winding of the relay BR is completed:—beginning at the terminal B+ of the battery 16, wire 35, upper winding of the relay BR, wire 36, contact 37 of the lever L in its left-hand position, wires 65 and 30, contact segment 23 of the arm A, wire 31, to common return wire C connected to the midpoint of battery 16. The closure of the circuit just traced operates the relay BR to the right-hand position, but simultaneously with the closure of the circuit just traced a circuit is closed for the upper winding of the relay AR, which operates the relay AR to the right-hand position. This latter circuit may be traced as follows:—beginning at the terminal B— of the battery 16, contact 28 of the lever L in its left-hand position, wire 27, upper winding of the relay AR, wires 26, contact 25 of the lever L in its left-hand position, wires 66 and 38, contact 3 and arm A of the synchronous selector in the dispatcher's office, message wire 15, arm A¹ and stationary contact 3 of the synchronous selector at the way station, wire 39, contact 40 of the track relay T, wires 41 and 42, back contact 43 of the relay Z, wires 44 and 45, winding of the relay Y and upper winding of the relay X in multiple, wire 46, to common return wire C connected to the midpoint of battery 16. The completion of this circuit operates the relays AR, X and Y to the left-hand position.

Since the relays AR and BR now both assume the left-hand position, the indicating relay IR remains de-energized. With the relays X and Y assuming the left-hand position the control relay Z is energized to its left-hand position through the circuit heretofore traced, except that the contacts 48 and 52 of the relays Y and X respectively now assume the left-hand position. With the polar contact 55 in its left-hand position and the neutral contact 56 of the control relay Z closed, the west bound signal WM or WD, depending upon whether the switch S is in the main track or the take-siding position, is permitted to clear, providing traffic conditions in advance of these signals are favorable.

We have now considered the operation of the system in so far as the control of the control relay Z by the lever L is concerned. In other words, we have considered energization of the control relay Z to its right-hand energized position, to its left-hand energized position, and also the manner in which this relay Z is de-energized upon movement of the lever L to its neutral position. It is now believed expedient to observe the functioning of the system in response to the passage of a train over the detector track circuit.

We have just assumed that the control relay Z is energized to its left-hand position in response to the lever L to its left-hand position. Let us further assume that the track switch S is in its main track position and that for this

reason the entering signal WM assumes the clear position. Let us further assume that a west bound train, in response to the proceed indication given the signal WM, moves from right to left and passes over the detector track circuit, thereby de-energizing the track relay T. With the track relay T deenergized, the message circuit which would otherwise have been completed at the third position of the synchronous selectors, has now been broken at contact 40 of the track relay T. This breaking of the message circuit at the contact 40 will of course effect de-energization of the control relay Z, but this is of little importance in that the signal WM is directly put to stop in response to dropping of the track relay T, by circuits not specifically shown, but illustrated in the Wight application Ser. No. 120,423 heretofore referred to, so that de-energization of the control relay Z may be tolerated, it being inconsistent to have any one of the signals at proceed while the track relay T is de-energized.

Opening of the contact 40 of the track relay T however produces an effect upon the apparatus in the dispatcher's office, and manifests to the dispatcher that this track relay T has been de-energized. For reasons heretofore explained the engagement of the contact segment 23 with suitable stationary contacts while the arm A engages the contact 2, completes energizing circuits for the bottom winding of the relays AR and BR, thereby operating both of these relays AR and BR to their left-hand position. Also with the message circuit intact at the way station the relays AR and BR are operated to their right-hand position. If on the other hand the contact arm A assumes the third position in engagement with the stationary contact 3 with the message circuit heretofore traced not completed in its entirety, because the contact 40 of the track relay T is included therewith and this contact 40 is now assuming its retracted position, it readily appears that the relay AR will remain in its left-hand position. The relay BR, however, will be operated to its right-hand position upon completion of the following circuit:—beginning at the terminal B+ of the battery 16, wires 35, upper winding of the relay BR, wire 36, contact 37 of the lever L in its left-hand position, wires 65 and 30, contact segment 23, wire 31, to common return wire C connected to the midpoint of the battery 16. The completion of this circuit operates the relay BR to the right-hand position, and since the relay AR has not been operated to its right-hand position, because the contact 40 of the track relay T was open, the relays AR and BR are now out of correspondence, thereby effecting energization of the indicating relay IR through the following circuit:—beginning at the terminal B+, contact 68 of relay BR in its right-hand position, wire 69, wind-

ing of the indicating relay IR, wire 70, contact 71 of the relay AR in its left-hand position, to the common return wire C connected to the midpoint of battery 16.

5 With the indicating relay IR energized, the lifting of the contact 21 breaks the circuits for energizing the bottom windings of the relays AR and BR, so that their condition of energization will not be changed when the 10 contact arm A again assumes the second position during its rotation. Lifting of the contact 74 of the relay IR, however, after first momentarily sounding the bell BL, completes the circuit for energizing the indicating lamp IL, which circuit may be traced as 15 follows:—beginning at the terminal B+, wire 75, contact 76 of the relay AR assuming the left-hand position, wire 77, contact 78 of the relay BR assuming the right-hand position, wire 79, contact 74 of the relay IR in 20 its raised position, wire 80, indicating lamp IL, wire 81 to common return wire C connected to the midpoint of battery 16.

Continuation of the operation of the synchronous selector system, irrespective of 25 whether rotating arms or stepping relays are used, does not change the indicating condition of the lamp IL unless either the lever L is moved or the track relay T again assumes 30 its energized position. In this connection attention is directed to the fact that relay IR is slightly slow-dropping, as conventionally shown, and therefore does not assume its de-energized position during the short time relay BR assumes its left-hand position during 35 movement of the arm A from contact 2 to contact 3.

As soon as the track relay T again assumes 40 its energized position and closes its contact 40, the circuit heretofore traced for the upper winding of the relay AR and including the message wire 15 is completed, thereby causing the relays AR and BR to assume corresponding positions and thereby effecting de- 45 energization of the indicating relay IR and extinguishment of the indicating lamp IL.

The system described thus enables the dispatcher to transmit three distinctive control conditions over the message channel completed at the third contact in its cycle of operation, and in addition to affording these three distinctive controls the system affords the transmission of an OS indication over the 55 same message channel this through the medium of means at the dispatcher's office for detecting the continuity of the message channel during the instant such message channel should be completed, and this ability to detect the continuity of the message circuit enables an OS indication, which can only exist when the control relay Z may be de-energized, to be transmitted. In other words, since the occupancy of the detector track circuit itself puts the signals EM, ED, WM, and 60 WD to stop, there is no need of having con-

trol relay Z energized, as far as the control of these signals is concerned, and for this reason the front contact 40 of the detector track relay T may be included in series with the message circuit controlling the relay Z. 70 Putting it still another way, the indication of occupancy of the detector track circuit and the clearing of signals associated therewith are non-conflicting conditions, and for this reason may both be carried on over the same 75 message circuit.

It is of course understood that each of the various contact points, or steps in the synchronous selector system, will afford the same number of indications as already described in connection with contact point 3. 80 Also, it is to be understood that the switch S may be operated by a switch machine controlled over another channel of the synchronous selector system, and if this is the case the operation of the switch machine is indicated by the switch box contact 13 associated with the switch S. In this connection it should be noted that this switch box contact 13 is in multiple with the back contact 85 43 of the control relay Z, so that the contact 13 must be closed while the controlling relay Z is energized to avoid de-energization of this control relay Z during the following 90 cycle of operation of the synchronous selector system.

In order to more clearly understand this feature of the circuit arrangement, let us assume that the switch box contacts 13 are 95 opened, possibly because of misadjustment of the switch S. In this connection the control relay Z may be picked up, in that this relay Z is controlled by the relays X and Y, and the relays X and Y may receive their control through the back contact 43 of the relay Z. 100 As soon, however, as the relay Z assumes its energized position the message circuit is 105 opened at the back contact 43 (contacts 13 being opened) so that during the next cycle of operation the relays X and Y will be operated 110 to their normal position and will effect de-energization of the control relay Z. In the third cycle of operation the control relay Z is again picked up, and it is again de-energized during the fourth cycle of operation. In 115 other words, the indicating lamp IL will be 120 flashed in accordance with this operation of the control relay Z and will indicate to the dispatcher that the track switch is in an intermediate position. It should be understood that, if desired, the back contact 43 may be 125 entirely omitted, in which event the failure of closure of contact 13 will result in illuminating indicating lamp IL and in holding the signals associated with the switch S at 130 stop. Also, if the switch S is operated by a switch machine, this operation of the switch machine is indicated through the medium of contacts 13. Further, if such switch machine 135 is employed, since as just brought out the 140

dispatcher has intermittent control over the relay Z, that is, may operate this relay Z to either of its polar positions even though contacts 13 are open, he is able to reverse the switch at mid-stroke.

5 Putting it briefly, the present system contemplates the use of two polar permanent magnet stick relays at each end of a message circuit, which polar relays will be operated to a certain position just before the message circuit by which they are controlled is completed, these polar relays being operated to a certain control position during the completion of such message channel, so that these 10 relays are reconditioned once during each operation of the synchronous selector system. Also, since two such polar permanent magnet stick relays are used in the dispatcher's office in connection with a particular message channel it is possible to determine whether such 15 message channel is actually completed in the field or not, and this feature may be taken advantage of and used for the purpose of transmitting OS indications from a way station to the dispatcher's office.

Having thus shown and described one 20 rather specific embodiment of the present invention, as applied to a synchronous selector system which has been conventionally shown, it is desired to be understood that the particular embodiment of the present invention 25 illustrated has been selected for the purpose of facilitating description of the underlying principles of the invention and its operating characteristics and has not been selected for the purpose of showing the scope of the invention or the exact circuit arrangement preferably employed in practicing the same, and that various changes, modifications, and additions may be made to adapt the invention to 30 the particular problem encountered in practicing the same, all without departing from the spirit or scope of the invention of the idea of means underlying the same, except as demanded by the scope of the following 35 claims.

What I claim as new is:—

1. In a train dispatching system of the synchronous selector type; the combination with a selector system including a message channel rendered available momentarily once during each cycle of operation of such system, a dispatcher's office at one end of said message channel, and a way station at the other end of said message channel; a polar-neutral relay at said way station; and means for controlling said relay to assume either of its energized positions or its de-energized position in response to the polarity of current or the absence of current transmitted over said message channel comprising, two polar relays having stick characteristics both energized to a particular polar position in response to current of corresponding polarity transmitted over said message circuit; means for operat-

ing one of said polar relays to the opposite position during the following cycle of operation, and circuits for causing said polar-neutral relay to assume a position depending on the position assumed by said polar relays; whereby said polar neutral relay will assume one energized position if said polar relays both assume one polar position, assume another energized position if both polar relays assume the other polar position and assume a de-energized position if said polar relays assume positions out of correspondence. 70

2. In a train dispatching system of the synchronous selector type; the combination with a selector system including a message channel rendered available momentarily once during each cycle of operation of such system, a dispatcher's office at one end of said message channel, and a way station at the other end of said message channel; a polar-neutral relay at said way station; and means for controlling said relay to assume either of its energized positions or its de-energized position in response to the polarity of current or the absence of current transmitted over said message channel comprising, means for establishing a local energizing circuit for said polar-neutral relay including a direct current source of one polarity, for establishing a local energizing circuit for said polar-neutral relay including a direct current source of the reverse polarity and for breaking the last made circuit in response to the transmission of current of one polarity or the other polarity over said message circuit or in transmitting no current over said message circuit. 90

3. In a train dispatching system of the synchronous selector type; the combination with a selector system including a message channel rendered available momentarily once during each cycle of operation of such system, a dispatcher's office at one end of said message channel, and a way station at the other end of said message channel, a lever at the dispatcher's office indicating means at the dispatcher's office, electro-responsive control means at said way station, means for controlling said electro-responsive means in response to a change of the position of said lever and over said message channel, and means for controlling said indicating means responsive to the continuity of said message channel during the time said message channel is available for use. 105

4. In a train dispatching system of the synchronous selector type; the combination with a selector system including a message channel rendered available momentarily once during each cycle of operation of such system, a dispatcher's office at one end of said message channel, and a way station at the other end of said message channel a lever at the dispatcher's office, indicating means at the dispatcher's office, electro-responsive control means at said way station, means for control-

ling said electro-responsive means in response to a change of the position of said lever and over said message channel, and means for controlling said indicating means including a relay of the snap-action type included in said message channel.

5. In a train dispatching system of the synchronous selector type; the combination with a selector system including a message channel rendered available momentarily once during each cycle of operation of such system, a dispatcher's office at one end of said message channel, a way station at the other end of said message channel, a lever at the dispatcher's office, indicating means at the dispatcher's office, electro-responsive control means at said way station, means for controlling said electro-responsive means in response to a change of the position of said lever and over said message channel, and means for controlling said indicating means in accordance with the continuity of said message circuit during the time said message channel is available including two polar relays of the snap-action stick type, one of which assumes an abnormal position if potential is applied to the message circuit and the other of which assumes an abnormal position if current flows over said message circuit, said indicating means assuming its indicating condition if said polar relays are out of correspondence.

6. In a train dispatching system of the synchronous selector type; the combination with a selector system including a message channel rendered available momentarily once during each cycle of operation of such system, a dispatcher's office at one end of said message channel, a way station at the other end of said message channel, a lever at the dispatcher's office, indicating means at the dispatcher's office, electro-responsive control means at said way station, means for controlling said electro-responsive means in response to a change of the position of said lever and over said message channel, and means for controlling said indicating means including a plurality of devices which assume corresponding positions if current flows in the message circuit and potential is applied to the message circuit but which assume noncorresponding positions if potential is applied to but no current flows in said message circuit.

7. In a train dispatching system of the synchronous selector type; the combination with a selector system including a message channel rendered available momentarily once during each cycle of operation of such system, a dispatcher's office at one end of said message channel, and a way station at the other end of said message channel; a lever at the dispatcher's office; indicating means at the dispatcher's office; electro-responsive control means at said way station; means for controlling said electro-responsive means in response to a change of the position of said lever and over said

message channel; and means for controlling said indicating means including means distinctively responsive to the application of potential to and the flow of current in said message circuit, which renders said indicating means active if potential is applied and no current flows in said message circuit.

8. In a selector system of the type in which a message circuit may be momentarily completed by the application of stepping impulses to a stepping line, the combination with a message circuit connecting a central office and a distant way station, of means employing the same message circuit for transmitting a control and receiving an indication comprising, traffic controlling means at a distant way station, stick electro-responsive means at said way station for controlling said traffic controlling means and controlled from said central office over said momentarily completed message circuit, means at said central office for detecting whether or not said message circuit is open at a distant point, and means for opening said message circuit at a distant point when an indication is to be transmitted.

9. In a centralized traffic controlling system, the combination with one circuit for transmitting impulses from a central office to a plurality of way stations, of a message wire connecting said central office and said way stations, of a particular message circuit including said message wire, a two-position indicating relay energized to be operated to a particular position during a particular impulse in a cycle applied to said one circuit providing an indicating contact in said particular message circuit is closed, and means for operating said relay to the opposite position at an earlier time in such cycle than the time of said particular impulse, whereby said relay assumes one position substantially continuously if said indicating contact is closed and assumes the opposite position continuously if said indicating contact is closed.

10. In a centralized traffic controlling system, the combination with a message wire connecting a central office and a distant way station, selector means located partly at said central office and partly at said way station and operable through a cycle of operation at a particular point in which a message circuit is closed including a contact at said central office and a contact at said way station, a two-position relay at said central office included in said message circuit with a source of current to operate said relay to a particular position upon closure of said circuit, an indicating contact in said message circuit at said way station to prevent such operation of said relay, and other means for operating said relay to its opposite position at a point in such cycle just preceding said particular point, whereby said relay substantially continuously assumes a position corresponding

to whether said indicating contact is open or closed.

11. In a centralized traffic controlling system, the combination with a message wire connecting a central office and a distant way station, selector means located partly at said central office and partly at said way station and operable through a cycle of operation at a particular point in which a message circuit is closed including a contact at said central office and a contact at said way station, a two-position relay at said central office included in said message circuit with a source of current to operate said relay to a particular position upon closure of said circuit, an indicating contact in said message circuit at said way station to prevent such operation of said relay, and other means for operating said relay to its opposite position.
12. In a centralized traffic controlling system, the combination with a message wire connecting a central office and a distant way station, selector means located partly at said central office and partly at said way station and operable through a cycle of operation at a particular point in which a message circuit is closed including a contact at said central office and a contact at said way station, a two-position relay at said central office included in said message circuit with a source of current to operate said relay to a particular position upon closure of said circuit, an indicating contact in said message circuit at said way station to prevent such operation of said relay, a traffic controlling device at said way station, means for controlling said traffic controlling device over said message circuit, and other means for operating said relay to its opposite position at a point in such cycle just preceding said particular point, whereby said relay substantially continuously assumes a position corresponding to whether said indicating contact is open or closed.
13. In a centralized traffic controlling system, the combination with a message wire connecting a central office and a distant way station, selector means located partly at said central office and partly at said way station and operable through a cycle of operation at a particular point in which a message circuit is closed including a contact at said central office and a contact at said way station, a two-position relay at said central office included in said message circuit with a source of current to operate said relay to a particular position upon closure of said circuit, an indicating contact in said message circuit at said way station to prevent such operation of said relay, a traffic controlling device at said way station, means for controlling said traffic controlling device over said message circuit, and other means for operating said relay to its opposite position.
14. The method for substantially continu-

ously indicating whether or not a contact is closed located at the remote end of an intermittently rendered available circuit, which resides in operating a two-position relay to a particular position when said circuit is available and said contact is closed, and in operating said two-position relay to the opposite position a moment before each instant said circuit is rendered available.

15. Means for substantially continuously indicating whether or not a contact is closed located at the remote end of an intermittently rendered available circuit comprising, a two-position relay and a source of current in said circuit for operating said relay to a particular position each time said circuit is rendered available and said contact is closed, and other means for operating said relay to the opposite position an instant before said circuit is rendered available.

16. Means for substantially continuously indicating whether or not a contact is closed located at the remote end of an intermittently rendered available circuit comprising, a two-position relay and a source of current in said circuit for operating said relay to a particular position each time said circuit is rendered available and said contact is closed, and other means for operating said relay to the opposite position just before said circuit is rendered available.

17. Means for substantially continuously indicating whether or not a contact is closed located at the remote end of an intermittently rendered available circuit comprising, a two-position relay and a source of current at the local end in said circuit for operating said relay to a particular position each time said circuit is rendered available and said contact is closed, and other means for operating said relay to the opposite position just before said circuit is rendered available.

In testimony whereof I affix my signature.

WALTER W. WENHOLZ.

DISCLAIMER

1,794,563. -- *Walter W. Wenzel*, Rochester, N. Y. TRAIN-DISPATCHING SYSTEM FOR RAILROADS. Patent dated March 3, 1931. Disclaimer filed February 16, 1934, by the assignee, *General Railway Signal Company*.

Hereby enters this disclaimer to claims 3 and 4 of said Letters Patent, which are in the following words, to wit:

"3. In a train dispatching system of the synchronous selector type; the combination with a selector system including a message channel rendered available momentarily once during each cycle of operation of such system, a dispatcher's office at one end of said message channel, and a way station at the other end of said message channel, a lever at the dispatcher's office indicating means at the dispatcher's office, electro-responsive control means at said way station, means for controlling said electro-responsive means in response to a change of the position of said lever and over said message channel, and means for controlling said indicating means responsive to the continuity of said message channel during the time said message channel is available for use.

"4. In a train dispatching system of the synchronous selector type; the combination with a selector system including a message channel rendered available momentarily once during each cycle of operation of such system, a dispatcher's office at one end of said message channel, and a way station at the other end of said message channel a lever at the dispatcher's office, indicating means at the dispatcher's office, electro-responsive control means at said way station, means for controlling said electro-responsive means in response to a change of the position of said lever and over said message channel, and means for controlling said indicating means including a relay of the snap-action type included in said message channel."
